UNITED STATES PATENT OFFICE.

EMIL RITZ, JR., OF CHEVIOT, OHIO, ASSIGNOR TO THE HISEY-WOLF MACHINE COMPANY,
OF CINCINNATI, OHIO, A CORPORATION OF OHIO.

INTERNAL AND EXTERNAL GRINDER.

Specification of Letters Patent. Patented Mar. 12, 1918.

1,259,130.

Application filed January 20, 1918. Serial No. 73,105.

To all whom it may concern:

Be it known that I, EMIL RITZ, Jr., a citizen of the United States, and a resident of the village of Cheviot, in the county of Hamilton and State of Ohio, have invented certain new and useful Improvements in Internal and External Grinders, of which the following is a full, clear, and exact description, reference being had to the accompanying drawing, forming part of this specification.

My invention relates to electrical tools for the grinding both externally and internally of castings or the like. In devices of this nature, the desired speed for a small grinder to be used in internal grinding cannot be applied to a large grinder for outside grinding, and accordingly one or the other of the operations cannot be done with a grinder directly driven from a motor shaft.

This fact has been recognized in the art and there have developed certain forms of grinders, wherein an extension member is provided for the internal grinding, which is belt or gear driven from a motor and the motor shaft itself used for the external grinding. There has been considerable difficulty found in constructing such external and internal grinders because in mounting the motor in a suitable bracket for moving the grinders during the work it has been necessary to mount the belt driven extension members for internal grinding on the rear of the motor away from the operator to get it out of the way of the operator in moving the motor on the bracket. Another difficulty has been that where the belt pulley on the motor has been to the left of the motor then it is in the way of the operator, and when it has been on the right of the motor, then in mounting the external grinding tool on the motor shaft in the place of the pulley, the work is thrown onto the opposite side of the motor from the internal work, and it is then necessary to provide an additional attachment to throw the external grinding operation to the proper side.

It is my object to provide against these difficulties as above stated, and this object together with other advantages which I will duly indicate I accomplish by that certain construction and arrangement of parts to be hereinafter more specifically pointed out and claimed.

In the drawing,

Figure 1 is a top plan view of the device.

Fig. 2 is a top plan view of the extension unit partly in section.

Fig. 3 is a front elevational detail showing the method of vertical adjustment.

Fig. 4 is a detail section through the mounting bracket.

Fig. 5 is a detail perspective view of the mounting block on the extension unit.

Fig. 6 is a perspective view of the mounting bracket.

The mounting bracket 1 is provided, said bracket being adjustable and movable on a suitable framework in the usual manner 70 that such tools are adjusted. The various parts of the internal and external grinder are to be mounted on this bracket. This bracket has a dovetailed groove 2, and mounted in a boss 3 in the bracket is a 75 worm 4 which extends slightly into the groove at its central portion and has an operating handle 5.

The extension unit has a mounting block 6 that has a dovetail 7 adapted to fit 80 the groove in the bracket, said dovetail having in its central portion a segmental cut 8 which is scored with worm convolutions 9 so as to mesh with the worm 4. Thus when the block is in the bracket it may be adjusted 85 up and down by means of the worm.

At the opposite side of the block is a dovetailed groove 10 of the same proportions as the groove 2 in the bracket, and the motor 11 has a mounting block 12 which has a dovetail 13 exactly corresponding to the dovetail on the block. This dovetail has likewise a segmental groove 14 similar to the groove or cut 8.

It is thus obvious that the motor may be 95 set in the mounting bracket just as the mounting block for the extension unit is set in, and that it will be similarly adjustable.

Journaled in the mounting block 6 is the extension shaft 15 which extends to the right 100 of the block a short distance and extends a considerable distance to the left of the block. Mounted on the block is a housing 16 for the left hand or working extension and on the right of the block is a housing 17 for 105 the right hand extension. There are self-aligning ball bearings 18 for the extension shaft in the housing 17 and at the right end of the shaft is the pulley 19.

At the other end of the extension shaft 110

housing is a cone-shaped bronze bearing 20, which can be adjusted, thereby giving to the working end of the shaft an accuracy of alinement which cannot be had with a ball 5 or roller bearing.

The motor shaft 21 has self-aligning ball bearings (not shown) similar to those of the extension shaft at the left end, but at the right end has a bronze bearing like that of 10 the extension shaft. At this right end of the motor shaft is to be mounted the driving pulley 22, which drives the pulley 19 on the extension shaft by means of a belt 23.

When the grinder is to be used for internal grinding, the extension unit is mounted 15 on the bracket and the motor on the extension unit. The grinder as at 24 is mounted on the extension shaft and the shaft driven as above indicated by the motor.

20 When the grinder is to be used for external work, where not so much speed is desired, then the motor is lifted out of the dovetail on the block 6 and the block 6 lifted out of the bracket. The motor is then 25 turned over and set into the bracket. It is evident that a large grinder can be placed on the motor shaft in the place of the driving pulley, and that the grinder will be at the left of the bracket in convenient position 30 for the operator, and that the motor will be vertically adjustable on the bracket by means of the worm.

It can be seen that the extension shaft in 35 this device is direct on the bracket instead of being on the motor. This gives rigidity to the said shaft and provides a much better mounting than if it was supported adjustably on the motor. The both forms of 40 grinding can be performed at the same side of the bracket and the motor is not between the operator and the extension shaft, nor is the belt and pulley device so placed that it is in the way of the operator.

The bearings are such that the full advantage of anti-friction bearings is gained 45 without the loss in accuracy attendant upon them, as it is found that the bronze bearing at the working end is all that is necessary. So also in the motor, whereby the working 50 end has a bronze bearing, and the shaft is still roller or ball mounted at one end.

It seems apparent that if a bracket having some other means than a dovetail were provided, it would be possible to apply both 55 motor and block to the bracket in some other

well known manner common to both, and I do not wish to limit myself to the dovetail mounting, nor to the feature of the mounting of the motor on the block by the same means that it is capable of being mounted 60 on the bracket.

It is not intended by the failure to mention all of the uses to which my invention may be put, or by the failure to note the various equivalents that might be substituted for those described without departing from the spirit of my invention, to exclude 65 from the claims that follow the full scope of equivalents in their construction.

Having thus described my invention, what 70 I claim as new and desire to secure by Letters Patent, is:—

1. In an external and internal grinder, a bracket, an extension unit for internal grinding mounted on the bracket, and a motor 75 for driving said unit mounted on said unit, and driving pulleys on the extension unit and the motor located to the one side of the bracket, and the extension unit extending from the other side of the bracket, for the 80 purpose described.

2. In a device of the character specified, a supporting bracket, a motor, and an extension member, the motor and the bracket provided with similar means for attachment 85 to each other, and with the extension member provided with corresponding means of attachment intermediate the motor and bracket.

3. In a device of the character specified, 90 a supporting bracket, a motor, and an extension member, the motor and the bracket provided with a corresponding groove and tenon respectively for attachment to each other, and the extension member provided 95 with a similar groove and tenon on opposite sides whereby the extension may be attached between the motor and bracket as desired.

4. In a device of the character specified, 100 a supporting bracket, a motor, and an extension member, the motor and the bracket provided with similar means for attachment to each other, and with means for adjusting the two parts in reference to each other, and an extension member provided with corresponding means of attachment intermediate the motor and bracket, and similar means for adjusting the extension member with reference to the two other parts.

EMIL RITZ, JR.
